DESIGN FORMING DEVICE

Gustav A. Carlson, Chicago, Ill., assignor to The
Boye Needle Company, a corporation of Illinois

Application September 27, 1935, Serial No. 42,499

5 Claims. (Cl. 28—15)

This invention relates to a design-forming device and more particularly to a device on which designs such as petals, flowers, etc. are formed by the use of yarn, thread, etc.

5 An object of the invention is to provide a design-forming device of extremely simple parts which enables the design to be conveniently formed and readily released.

10 A further object is to provide a design-forming device constructed of very few parts and which is provided with a pedestal by which the device is supported in upright position.

15 A further object is to provide a design-forming device equipped with vertically movable means for releasing the design-forming prongs from the thread design. Other specific objects and advantages will appear as the specification proceeds.

The invention is illustrated in preferred embodiments, by the accompanying drawing, in which—

Fig. 1 is a plan view of a device embodying my invention, yarn being shown applied to the prongs or fingers to form a petal flower design; Fig. 2, 25 a side view in elevation; Fig. 3, a plan sectional view, the section being taken as indicated at line 3 of Fig. 2 and the yarn being removed; Fig. 4, a vertical sectional view, the section being taken as indicated at line 4 of Fig. 1, the prongs being 30 shown in releasing position; Fig. 5, a bottom plan sectional view of a modified form of device embodying my invention, the section being taken as indicated at line 5 of Fig. 6; and Fig. 6, a vertical sectional view, the section being taken as 35 indicated at line 6 of Fig. 5 and the prongs being shown in releasing position.

In the illustration given in Figs. 1 to 4, inclusive, 10 designates an upper forming plate and 11 a pedestal plate. The two plates 10 and 11 are 40 connected to the ends of a fixed stem 12.

A sleeve 13 is slidably mounted on the stem 12. Fixed to the lower end of sleeve 12 is a presser plate 14. Fixed to the upper end of sleeve 13 is a prong plate 15. The prong plate 45 15 is preferably formed in one piece and of suitable flexible material such as cellulose acetate, resilient metal, etc. Portions of the plate are cut away so as to provide a series of spaced fingers or prongs 16, the prongs extending a certain distance beyond the periphery of plate 10, as shown more clearly in Figs. 1 and 3. If desired, a spring 50 17 may be placed between plates 11 and 14 so as to normally urge the prong plate 15 against the forming plate 10. The device may, however, be 55 operated without a spring.

In the operation of the device, a yarn or other thread 18 may be drawn about the ends of the prongs 16 and over the forming plate 10, as illustrated in Fig. 1 so as to form a flower or other suitable design. After the design has been 5 formed, it is released from the device by pressing plate 14 downwardly, as illustrated in Fig. 4, the flexible fingers 16 bending and giving the dished appearance shown in Fig. 4. When the plate 14 is depressed slightly further, the ends of the prongs 10 16 slip out of the design and the flower or other design may be removed. Immediately after the removal of the design, the spring 17 moves the sleeve 13 and prong plate 15 back into the operative position illustrated in Figs. 1 and 2. 15

The device can be operated with great speed, the designs being quickly formed and released from the prongs instantaneously by downward movement of the presser plate 14.

In the modification shown in Figs. 5 and 6, the 20 construction of all of the members is substantially the same as illustrated in Figs. 1 to 4 except that the plate 15^a is rigid and is provided with a series of slots having transverse pivot pins 20 extending therethrough. Mounted on the 25 pivot pins 20 are a plurality of fingers 21, each of the fingers having its lower end turned upon itself to provide a hinge 22 extending about pin 20.

The modified construction of Figs. 5 and 6 30 operates substantially the same as the device shown in Figs. 1 to 4. However, instead of having the plate 15^a flex together with the prong fingers, the plate 15 remains in horizontal position while fingers 21 swing upon their pivots 20 35 as the plate 15^a moves upwardly and downwardly. When the plate 15^a is in its upper position, the prongs 21 are in extended and substantially horizontal position so as to engage the yarn, etc. After the design has been formed, the presser 40 plate 14^a is moved downwardly against the force of spring 17^a and the fingers 21 move to the releasing position shown in Fig. 6. A slight further downward movement of sleeve 13^a causes 45 the fingers 21 to be released from the design. 50

While, if desired, an outer casing may be provided for enclosing spring 17 and other changes of like character may be made, without departing from the spirit of the invention, it is believed that the present design is advantageous in that it is 50 constructed of few parts all of which are readily accessible and because of the ease with which the sleeve can be vertically adjusted on the stem. It will be observed that the prongs, when the sleeve 55 is moved to the upper position, are held rigidly

against displacement. They cannot be moved inwardly and the tendency of the yarn which is drawn about the prongs is to draw the prongs tightly against the bottom of forming plate 10. 5 When it is desired to release the design, however, the fingers yield readily to bring about disengagement when the presser plate is pressed down.

The foregoing detailed description has been given for clearness of understanding only, and no 10 unnecessary limitations should be understood therefrom, but the appended claims should be construed as broadly as permissible, in view of the prior art.

I claim:

15 1. A design-forming device comprising: a pair of plates, a stem fixed to said plates and supporting them in spaced relation, a sleeve movably mounted on said stem, a prong plate carried by said sleeve and being provided with yieldable 20 prongs extending beyond the periphery of said plate, and spring means urging said sleeve toward raised position.

2. A design-forming device comprising: a forming-plate, a pedestal plate, a stem connecting said 25 plates, a sleeve slidably mounted on said stem, a prong plate carried by the upper end of said sleeve and having yieldable prongs extending beyond the periphery of said forming-plate, a presser plate secured to the lower end of said sleeve, and 30 a compression spring extending about said stem, and between said pedestal plate and said presser

plate, said spring urging said presser plate toward raised position.

3. In a device of the character set forth, a forming-plate, a stem secured thereto, a vertically movable plate carried by said stem, said movable plate being provided with fingers normally extending beyond said forming plate and in engagement with a thread design but moving inwardly with respect to the periphery of said forming-plate when said fingers are withdrawn from said thread design as said movable plate is moved downwardly. 10

4. In a device of the character set forth, a forming plate, a stem secured thereto, a plate movably supported on said stem, and a plurality of 15 fingers pivotally secured to said last-mentioned plate and having their end portions extending beyond the periphery of said forming plate when said last-mentioned plate is in raised position.

5. In a device of the character set forth, a 20 forming plate, a pedestal plate, a stem connecting said plates, a sleeve movably mounted on said stem, a pair of plates secured to the ends of said sleeve, the upper plate of which is equipped with 25 yieldable prongs normally extending beyond said forming-plate, said prongs when engaged by thread extending over said forming-plate being movable inwardly with respect to the periphery of said forming-plate to be disengaged from said thread as said sleeve is moved downwardly. 30

GUSTAV A. CARLSON.
